COMBINATION POST SUPPORTED LIGHT, LOUD SPEAKER, AND TABLE

Josef Johann Hammes, Maplewood, Mo., assignor to
Benjamin W. Lowell, St. Louis, Mo.

Application July 31, 1958, Serial No. 52,003

Term of patent 14 years

(Cl. D48—31)

Figure 1 is a view in elevation of my combination post supported light, loud speaker and table showing my new design;

Figure 2 is a view in elevation taken similarly to Figure 1, but with the combination post supported light, loud speaker and table rotated 45 degrees on its axis; and

Figure 3 is an enlarged sectional view on the line 3—3 of Figure 2 showing the design of the light globe. The table member located on the top of the scroll elements is circular and plain. The loud speaker baffle element as seen from the bottom of the loud speaker is conventional in appearance.

I claim:

The ornamental design for a combination post supported light, loud speaker, and table, as shown and described.
